UNITED STATES PATENT OFFICE.

SANDOR A. MARCHFIELD, OF NEW YORK, N. Y.

LOCK.

1,190,439.

Specification of Letters Patent. Patented July 11, 1916.

Application filed October 25, 1915. Serial No. 57,750.

To all whom it may concern:

Be it known that I, SANDOR A. MARCHFIELD, a citizen of the United States, residing at New York, in the county of New York and State of New York, have invented new and useful Improvements in Locks, of which the following is a specification.

This invention relates to improvements in locks as used upon swinging doors of various types, where adequate protection is desired, the lock being of the cylinder class.

One of the objects of the invention is to provide a lock having a plurality of bolt elements, in place of a single bolt as usually employed, one or more of which may engage with the threshold or casing of the door at points remote from the lock, transversely to the main horizontal bolt.

Another object is to provide tumblers which cannot be damaged by attempts at driving into them, whereby they may be forced and the lock opened unauthorizedly.

Another object is to provide means whereby the lock may be operated from the inner side of the door, irrespective of the condition of the tumbler barrel, and finally to provide means whereby, should the barrel stem be removed by force or otherwise, that the bolts would still remain in a locked position and in which it is impossible to re-adjust the operative parts from the exterior of the door.

These and other objects are attained by the novel adaptation, combination and construction of parts hereinafter described and shown in the accompanying drawing, forming a material part of this specification, and in which:

Figure 1 is a greatly reduced, partial view of a lock, showing its application to a door upon the inner side thereof. Fig. 2 is an enlarged view of the locking mechanism, partially in section, the view being taken substantially on line 2-2 of Fig. 3. Fig. 3 is a vertical sectional view of the same, taken on line 3-3 of Fig. 2. Fig. 4 is a further enlarged longitudinal view showing the main operative parts. Fig. 5 is a transverse sectional view, taken on line 5-5 of Fig. 4, and Fig. 6 is a perspective view of one of the tumbler pins.

In the drawings, the numeral 10 represents the front portion of the door, bored, as at 11, to receive the stem and counter-bored

at 12, for the barrel, which is disposed upon the outer side of the door.

On the inner side of the door is attached a casing 13, the keeper 14 being secured as usual to the jamb of the door.

Within the casing 13 are two slidable bolt elements 16 and 18, connected by a rigid integral bar 17, the bolts being guided by the recessed member 19, formed with a fixed stop 20 at its inner end. Also formed with the bolt 18 is a rearwardly extending arm 22 having rack teeth 23, the same engaging with the teeth on the elongated pinion 24, mounted to rotate freely within the casing 14 and provided with a stem 25 which extends outwardly beyond lock casing 13 and has pinned to it a knurled knob 26 by which it may be rotated. The pinion is held normally against the inner cover 28 of the lock by means of the coiled push spring 29 which abuts at one end against the pinion 24, and at the other against the flanged extension 30 of the casing 15. Engaged with the pinion 24 is a rack 32 connected by a rod 33 to the cylindrical bolt 35, engaging through the plate 36 with the threshold or floor 37, the rod 33, which is screw-threaded at its ends, being incased in a tube 37 held in clips 34 and secured at its upper end with the lock casing 15. Thus when the knob 26 is rotated, the bolts 16, 18 and 36 may be advanced or retracted as desired, and it will be obvious that another bolt may be similarly operated through the rack 24 and engaged with the frame at the top of the door.

The barrel 40 having the projecting flanged escutcheon plate 41, through which the key enters, is secured in the opening 12 on the outer side of the door and is of the well-known cylinder lock pattern.

The key passing into the lock through the opening 42 engages with a series of pins 43 having conical ends 44 and adapted to make contact with the sinuosities of the key as it is entered, the pins 43 being of hardened steel, in place of the usual soft material employed, rendering it impossible to drill into the lock whereby the pins would be rendered useless and the lock opened unauthorizedly. These pins are pressed toward the key when in normal condition by means of short rods 45 actuated by the coiled helical springs 46, so that the cylinder 48 is prevented from turning except when the joints

49 between the pins and rods are in register with the periphery of the cylinder 48.

- At the rear end of the cylinder 48 is a rectangular stem 50, and engaged with the stem is a rectangular bar 51 formed with a slot 52 and clamped by the bolt 53, a rectangular enlargement 54 extending into an opening 55 formed in the pinion 24, the enlargement terminating in a pin 56, revoluble 10 in the bearing 57 formed in the pinion and by which it is maintained normally in alignment with the key barrel. Should the tumbler barrel be removed as by force or otherwise, and the pin 56, together with the driver 15 54 be withdrawn from the pinion, the latter element is raised at its inner end angularly by means of the flat spring 60, the stem 25 being loosely fitted to pivot within the flanged extension 30 for this purpose.
- 20 Thus it is not possible to re-connect these parts from the exterior of the door and obviously control of the several bolts becomes lost and cannot be obtained from the outside.
- 25 Having thus described my invention and pointed out its construction, purpose and use, what I claim as new and desire to secure by Letters Patent, is:—

1. In a lock of the class described, the combination with a casing, a bolt movable horizontally therein, said bolt having two spaced extending elements, a vertically movable bolt, means for actuating said bolts simultaneously, said means being operated by a 30 knob upon one side and by a key on the

other; means for disengaging said key operated means from said actuating means and means for preventing reengagement of said actuating means.

2. In a lock of the class described, the combination with a casing, bolts movable therein, and a rack combined therewith, of a pinion engaging said racks revoluble in said casing, said pinion being inclinably mounted, a knob for actuating said pinion, a key 40 barrel having hardened pins operative therein, a cylinder rotatable within said barrel, an adjustable connection between said cylinder and said pinion, said connection having a part normally maintaining said pinion in 45 a horizontal position and means preventing the re-insertion of said part after withdrawal.

3. In a lock of the class described, a casing, one or more bolts slidable in transverse planes in said casing, racks combined with said bolts, a pinion common to all of said racks, direct means for rotating said pinion on one side of the lock, a key operated rotating means on the other, a pivot mounting 55 60 for one end of said pinion, an extension from said key operating means entering said pinion at the other, and means, operative upon the withdrawal of said extension, for raising said pinion out of alignment 65 therewith and preventing its reentrance.

In testimony whereof I have signed my name to this specification.

SANDOR A. MARCHFELD.
